UNITED STATES PATENT OFFICE.

CHARLES EDWIN BURCH, OF PANAMA, NEW YORK.

PROPELLING VESSELS BY EXHAUST-STEAM.

SPECIFICATION forming part of Letters Patent No. 313,981, dated March 17, 1885.

Application filed November 22, 1884. (No model.)

To all whom it may concern:

Be it known that I, CHARLES E. BURCH, of Panama, in the county of Chautauqua and State of New York, have invented an Improved 5 Means of Using Steam as a Motor, of which the following is a specification.

The special object of this invention is to provide means to utilize to a greater extent than is now done the motive power of steam 10 in its application to high-pressure engines on land and water vehicles.

The invention will first be described in connection with the drawings, and then clearly pointed out in the claim.

15 Figure 1 of the drawings shows the exhaust ports of an engine-cylinder connected with a tube discharging rearwardly of the line of motion. Fig. 2 is a longitudinal vertical section of a steam-vessel, showing two ways of running the tube.

In the drawings, A represents the propeller, and B the shaft which rotates it. The latter has a crank, b, which is turned by the reciprocation of the piston-rod C.

25 E is an engine-cylinder having exhaust ports e e. Up to this point all is old and already well known to the public. With these exhaust-ports I connect a pipe, F or F', which is brought into a horizontal range or line par-

30 allel to the keel, and with its mouth or outlet pointing rearwardly or toward the stern of the vessel. In this position the vacuum-force in the cylinder will force the exhaust-steam against air or water and assist in propelling 35 the vessel, the air or water serving as an abutment while the movable vessel is forced forward. In this way the live and exhaust steam co-operates to actuate a locomotive or a water vehicle. As all high-pressure engines must

40 overcome the resistance of the atmosphere before they can produce locomotion, it is a matter of no small importance to counterbalance this resistance, and thus economize the cost of propulsion. There are, doubtless, times

when the winds and waves will somewhat interfere with the working of pipe F at the stern; but the upper pipe, F', may be arranged on a circular iron railing and readily adjusted to the direction of the boat by telescoping joints. This pipe will therefore always be in order 50 and held firmly to the railing.

My invention is equally applicable to a side-wheel steamboat or any craft which is driven by a high-pressure engine. Of course the shorter the distance traveled by the exhaust steam, the less the friction and the greater the amount of the power utilized; hence the tube F or F' should be as short as possible and as free from turns or bends as possible.

55 I am aware that it is not new to discharge 60 air, water, or steam against another fluid for the purpose of forcing forward the movable body from which it was discharged; but I am not aware that means have ever been combined so as to make both the live and exhaust 65 steam co-operate in moving a land or water vehicle.

I am aware that it is not broadly new to force steam against water on either side of a vessel in order to steer, or against water in 70 the rear of vessels for the purpose of propelling; hence I desire to disclaim any discovery or invention thereof on my part; hence

75 What I desire to protect by Letters Patent is specified in the following claim:

The combination, with a high-pressure engine arranged on a land or water vehicle and connected with mechanism operated by its live steam to drive said vehicle, of the tube F F', open at both ends, connected with the 80 exhaust of engine, provided with the cocks e e f f' g, and having its discharge ends pointing rearwardly of the vehicle, as shown and described.

CHARLES EDWIN BURCH.
